2 Claims. (Cl. 34—52)

1

This invention relates to the variation of the physical state of materials such as the dampness of cloth, and in particular to apparatus for achieving this purpose by utilising the effect of variation of the physical state on a condenser of which the material forms all or part of the dielectric.

The main object of the present invention is to provide means for varying the speed of travel of a continuous or long piece of the material through a treatment zone in which the physical characteristic to be controlled is varied, the variation in speed being dependent upon variation of the physical state from a required standard. For example cloth may be passed through a drying oven to control its humidity. If the cloth emerging from the oven is too damp the speed of the material through the oven will be decreased and vice versa.

According to the present invention a method of varying the physical state of a material comprises moving the material through an oven or other treatment zone, deriving a voltage which is proportional to the dampness or other physical state of the material, said voltage being derived only at predetermined regular distances along the material, and positively or negatively accelerating the motion of said material for periods of acceleration proportional to the voltage so derived.

Thus in accordance with the invention the material is tested only at regularly spaced intervals and the speed of movement of the material through the treatment zone is varied at similar intervals if the physical state varies from the required value the variation of speed being in the required corrective direction and to a degree proportional to the degree of variation from the standard. The rate of variation of the speed may be constant, and the duration of this variation being proportional over the control range to the degree of variation from the standard.

An apparatus for carrying out the invention may comprise means for moving the material through an oven or other treatment zone, means for positively and negatively accelerating the motion of said material, voltage-deriving means for deriving a voltage which is proportional to the dampness or other physical state of the material, means for rendering the voltage-deriving means operative only at predetermined regular distances along the material, and relay means controlled by the derived voltage so as to accelerate said motion positively or negatively for

2

periods of acceleration proportional to said voltage.

The derivation of periods of acceleration from and proportional to the degree of said voltage may be effected by applying the voltage to the grid of a valve the current through which varies according to the said voltage, the anode of said valve being connected to a condenser which is periodically discharged by means of a gas-discharge tube, which completes a relay circuit. Two such valve-and-tube circuits may be provided fed with voltage of opposite polarity and serving to initiate and stop the positive or negative accelerations.

15 The movement of the material through the oven may be effected by an electric motor the speed of which can be altered by altering the position of its brushes by means of a pilot motor controlled by the relay.

20 For rendering the current-deriving means operative only at predetermined intervals a commutator device may be provided in the high-tension lead to the valve whereby the high-tension voltage is switched on only at the required intervals, the speed of the commutator being controlled so that the said intervals correspond with similar lengths of material irrespective of the speed of travel of the material.

25 A constructional form of the invention will now be described by way of example with reference to the accompanying diagrammatic drawings in which:

Figure 1 shows the electrical layout of an apparatus for deriving appropriate voltages;

30 Figure 2 shows the electrical layout of additional apparatus to be used in conjunction with the apparatus shown in Figure 1, for controlling the speed of cloth through an oven in accordance with the present invention;

35 Figures 3 and 4 are graphs to be referred to; and

40 Figure 5 shows a detail to be described.

An oscillator triode 10 has its grid connected by a suitable grid-lead 11 to earth, this grid-lead having a by-pass condenser 12 connected across it. The anode is connected to one plate of a fixed condenser 13, between the other plate of which and earth is a variable tuning condenser 14. This condenser is motor operated and the condenser and motor will be hereinafter more fully described. The anode is also connected to a position between two inductance coils 17, 18, which are in series and the second of which is connected to one plate of a fixed condenser 19, the other plate of which is connected to one terminal of a

switch 20 the other terminal of which is earthed. The switch 20 is operated by a relay controlled by a commutator to be described later. The other coil is connected to one plate of a condenser 21 the other plate of which is earthed, and it is also connected to a high-tension supply and by a choke coil 22 to the anode of a pentode amplifier valve 24 the control grid of which is connected by a fixed condenser 25 to the triode cathode, the latter also being connected to earth through a suitable choke 26 and to one plate of another condenser 27 the other plate of which is connected to the triode anode. The cathode and control grid of the pentode are also earthed through suitable resistances 28, 29 respectively. The anode of the pentode is connected to one plate of a condenser 31 the other plate of which is connected to earth through two inductance coils 32, 33, in series, which are coupled respectively with inductance coils 34, 35 respectively in two tuned circuits. The standard circuit contains a variable resistance 36 and variable condenser 37 while the measuring circuit contains the plates 38 between which the material is passed, both circuits being earthed by lead 40. The inductance coils 32, 33, are connected to the cathode of a diode detector valve 42 the anode of which is connected to the control grid of a second pentode valve 43 the cathode of which is earthed and between this anode connection and earth are a condenser 44 and a resistance 45 in parallel. The second pentode anode is fed with high-tension current through a resistance 48 in parallel with a condenser 49, and is connected by a condenser 50 to the control grid of a third pentode valve 51, this grid being also earthed through a resistance 52; the cathode of valve 51 is earthed through a resistance. The anode of the third pentode is connected through the primary coil 53 of a transformer to the high-tension supply, a shunt resistance 54 being provided across this coil. The secondary 55 of this transformer has contact points 57, 58, engaged alternately by a movable switch member 59 which is operated by a relay in synchronism with the switch 20. The mid-point of this secondary is earthed by a lead 60 so that, as will be more fully described hereinafter, the opposite ends, 61, 62, of the transformer are of opposite polarity. The switch member 59 is connected to a condenser 64 which is earthed and in parallel with this condenser is a smoothing resistance 65 and condenser 66. A lead 67, between the smoothing resistance and condenser, is taken to the device for controlling the physical state of the material under test which is described below. The other grids of the pentode valves are provided with any normal connections customary to their use as amplifying valves. Leads 68, 69, are connected to high-tension supply—positive and negative respectively.

The construction and operation of the parts 14, 20, and 59 is shown more fully in Figure 5. The condenser 14 comprises a series of fixed plates 71 which are quadrantal in shape and a series of movable plates 72 which are earthed by a slip ring (not shown) and have a similar shape to the fixed plates. The movable plates are fitted on to a rotatable spindle 73 and are symmetrically arranged so as to form two diametrically opposite sets. Rotation of the spindle is effected by a small motor 74.

The spindle 73 carries a commutator 75 which is composed of alternate quadrants of conducting and insulating material. The commutator is en-

gaged by two brushes 80, 81, the former of which is connected to a relay 76, and the latter of which is earthed. Relay 76 controls switches 20 and 59; when the relay is not energised switch 20 is open and switch member 59 makes contact with contact 57; when the relay becomes energised switch 20 closes and switch member 59 simultaneously moves over to contact 58. By this arrangement one set of plates 72 will move through approximately 90 degrees whilst the second inductance coil 18 and condenser 19 are included in the oscillator circuit thereby sweeping a frequency band which includes the resonant frequency of the standard circuit and a pulse of negative polarity is taken from the contact 56 end of the transformer secondary 55; whereupon the commutator causes the relay 76 to open switch 20 and reverse switch 59 so that the second inductance coil is no longer included in the circuit and during the next 90 degrees of revolution of the condenser plates a different frequency band will consequently be swept which includes the resonant frequency of the measuring circuit, and a pulse of positive polarity is taken from the contact 57 end of the transformer secondary. During the next 180 degrees of movement of the condenser plates the effect is repeated with the other set of movable condenser plates. It is arranged that the tuning condenser is at a maximum or minimum value when the second inductance coil is switched in or out of the oscillator circuit so that each frequency band is covered in one direction.

In the arrangement described above voltages are derived from both the standard and measuring circuits which are amplitude modulated by the oscillations supplied by the oscillator. The amplitude in each tuned circuit is a maximum when the oscillator frequency coincides with the resonant frequency of the tuned circuit. These voltages are applied to a diode rectifier to effect demodulation. The resultant signal has a pulsatory wave form which is amplified by the second pentode after which the pulses from one circuit are made negative and the pulses from the other circuit are made positive by means of the change-over switch 59 with a view to adding them in order to obtain the arithmetical difference. For this purpose the pulses are applied to the grid of the pentode valve in the anode lead of which is the transformer 53, 55 the secondary coil of which as already described has its centre point connected to earth so that pulses of opposite polarity derived from the two tuned circuits are developed across that half of the secondary brought into action by switch 59. The condenser 64 accordingly receives alternate positive and negative charges. The pulses are smoothed by means of the condenser 66 and resistance 65, thereby giving a D. C. level of voltage corresponding to the difference in the magnitude of the pulses.

If the final output difference is negative the "Q" value of the measuring circuit is too small and the material is too wet. If the voltage difference is positive the "Q" value of the measuring circuit is too large and the material is too dry. If the voltage is zero the two "Q" values are the same and the material has the required moisture content.

The apparatus so far described comprises the subject of co-pending British patent application No. 28,177 of 1945 in which it is more fully described.

For the purpose of the present invention the 75 additional apparatus shown in Figure 2 is pro-

vided in which 55 is the same transformer secondary coil as is shown in Figure 1, and the switch 59, contacts 57, 58, condenser 64, resistance 65, condenser 66, and output lead 67, also represent the same parts as are indicated by the same numerals in Figure 1.

The voltage across condenser 66 is proportional to the deviation in wetness of the material from the standard. If the material is too dry this voltage is positive while if this voltage is negative the material is too wet.

Another voltage is obtained by a lead 80 (taking the place of the lead 60) from the centre tapping point of the coil 55, this voltage being smoothed by condenser 81 and resistance 82. A condenser 83 is also provided corresponding to the condenser 66. The voltages across condensers 66 and 83 are therefore equal but of opposite polarity. Thus if the original voltage across condenser 66 is illustrated by the graph Figure 3, the voltage across condenser 83 will be as illustrated by Figure 4.

These voltages are applied respectively to separate similar circuits. The first of these circuits includes a pentode valve 86 to the control grid of which the lead 67 is connected. The cathode of the valve is connected by way of a resistance 90 to the earthed negative pole of a high-tension supply. In the anode lead of the pentode valve are a condenser 87 and a resistance 88 in parallel; the anode side of condenser 87 is connected to the cathode of a gas-discharge tube 91; the other side of the condenser is connected to the positive pole of the high-tension supply and to one end of an energising coil 92 the other end of which is connected to the travelling contact of a single-pole double-throw switch 93. One fixed contact 93A of this switch is connected to the anode of the gas-discharge tube 91 and the other fixed contact 93B is connected to earth through another energising coil 94 the purpose of which will be described later. The second of the aforesaid two circuits comprises similarly connected valve 96, condenser 97, resistances 98 and 100, gas-discharge tube 101, coil 102, switch 103, and coil 104. The coil 92 actuates the switch 93. When coil 92 is not energised the travelling contact rests on contact 93A; when energised the travelling contact moves to contact 93B and is there held on till the circuit external to the relay is broken, as will be described later. Coil 102 actuates the switch 103 in like manner to connect 102 alternatively to the anode of the gas-discharge tube 101 in the other circuit by way of fixed contact 103A or to coil 104 by way of fixed contact 103B.

The current through each of the pentode valves varies according to the potential applied to the grid. The condenser in the anode lead is thus charged at a rate which depends on the current and consequently on the potential applied to the grid, this potential being proportional over the working range of the apparatus to the degree of variation of the dampness of the cloth from the standard. If the voltage applied to the grid is positive the condenser charges up quickly but if this voltage is negative a comparatively long period is required to charge the condenser. The condenser charges up until the plates reach the potential of the striking voltage of the gas-discharge tube which accordingly becomes conducting thereby completing a circuit through 92, the tube 91, and switch 93 (by contact 93A). Thereupon, coil 92 being energised, switch 93 operates

and completes a circuit from the positive high-tension supply through 92, 93 (by contact 93B), and 94 to the negative high-tension pole, thereby energising coil 94. Hence the time taken to complete the latter circuit depends on the time at which the gas tube flashes. If a large positive voltage (indicating too dry material) is applied to the grid of the pentode 86 the coil 94 is energised almost immediately; if a small positive voltage is applied to the grid, switch 93 will not move as soon; and if a negative voltage, indicating too wet material, is applied to the grid, switch 93 will not move until after a comparatively long period. The other circuit behaves similarly except that, since the current input to its pentode valve 96 is of opposite phase, quick energisation of coil 104 indicates too wet material and slow energisation too dry material.

The coils 94, 104, actuate two relay switches 106, 107, respectively. Switch 106 has four contact points, 111, 112, 113, 114, and switch 107 also has four contact points 115, 116, 117, 118. Points 112, 113, 115, 118, are all connected together electrically in a permanent manner. Contacts 114 and 117 are also connected together and to one lead from the supply for the windings of a split field pilot motor 120. Contacts 111 and 116 are respectively connected to the ends of the two field windings of the motor, the common point of the windings being connected to the other supply lead. The pilot motor drives a toothed member 121 which carries the brushes of the main motor 14 which in turn drives a roller 123 that conveys the material 124 through an oven 125 that contains the testing condenser 38 of Figure 1. The contact 111 is connected to that field winding of the pilot motor which effects an increase in the speed of the main motor while contact 116 is connected to that winding which effects a decrease in the speed of the main motor. The contacts 113, 114, and 117, 118, are connected by the movable contacts of relays 94 and 104 when these relays are not energised and then there is no current to the pilot motor so that the main motor speed is unaltered. When relay 94 is energised its movable contact connects contacts 111, 112, instead of contacts 113, 114, and when relay 104 is energised its movable contact connects contacts 115, 116, instead of contacts 117, 118.

If for example the cloth is very dry a large positive voltage is applied to the grid of the pentode associated with relay 94 so that the movable contact of switch 106 will change from contacts 113, 114, to contacts 111, 112 almost immediately. The field winding current of the pilot motor then has a path through contacts 117, 118, and contacts 111, 112, and operates the pilot motor to accelerate the main motor so that the cloth passes more quickly through the oven and does not get so dry. At the same time a large negative voltage is applied to the grid of the pentode 96 and the movable contact of switch 107 therefore changes at a later time from contacts 117, 118, to contacts 115, 116. The contacts 113, 114, and 117, 118, are now both open so that current controlling the relay has no outlet path and the motor therefore stays at its altered speed. The motor is therefore positively or negatively accelerated in the period between the operation of the switches 106 and 107, and this period is approximately proportional to the degree of variation of the dampness from the standard.

The speed of the motor is not continuously varied but variation is effected at intervals corresponding to intervals of distance along the

cloth at which periodic tests are made. Thus upon making a test on one part of the cloth adjacent to the outlet end of the oven i. e., if the condenser 38 is located at the outlet end of the oven, the speed of the next length of cloth (equal to the length of the oven) is altered according to the degree of deviation of that part from the required standard of humidity. This is effected as follows. In the high-tension lead 128 to the pentode anodes is a disc 129 of insulating material which is rotated by geared connection to the main motor so that the disc makes one revolution in the period during which one position on the cloth travels the length of the oven. As the speed of the motor alters so does the speed of this disc. At one position on the circumference of this disc is a small piece 130 of conducting material. As the disc rotates high-tension current is applied to the valves through this conducting piece once for a short period during each revolution of the disc. The valves are therefore only effective during these short periods and consequently only at these intervals is the test made on a small part of the cloth and the speed of the motor altered accordingly. This disconnection of the high-tension supply at the end of each short period de-energises the coils of relays 92 and 102 thus causing them to restore, i. e. the travelling contacts to move from fixed contacts 93B and 103B to fixed contacts 93A and 103A respectively.

The main motor 74 also drives the switch 20, condenser 14, and switch 59, so that the operation of these parts is suitably related to the operation of the disc 129.

Should it be desired to effect control more frequently than the length of the oven allows, the condenser plates between which the cloth passes for test purposes are placed nearer to the point of entry of the cloth into the oven. By this arrangement allowance is made for drying subsequent to the measuring position. The length of cloth over which correction is made at corresponding intervals is that between the start of the oven and the measuring position.

We claim:

1. An apparatus for controlling the movement of material in accordance with variations in the

physical state thereof comprising means for moving the material relative to a treatment zone, means for positively and negatively accelerating the motion of said material, voltage deriving means for deriving two control voltages one of which is positive, and the other of which is negative according to the direction of deviation from a standard and each of which is proportional to the dampness or other physical state of the material, means for rendering the voltage deriving means operative only at predetermined regular distances along the material, a pair of condensers adapted to be charged at rates dependent on the polarities and potentials of said control voltages respectively, means for discharging the condensers when predetermined potentials are reached, and relay means operated by the discharging current and controlling the operation of said accelerating means so as to accelerate said motion positively and negatively according to which of the condensers discharges first, said relay means being also operated to stop the acceleration when the other condenser discharges, whereby the period of positive or negative acceleration is proportional to the period between discharging of the two condensers.

2. An apparatus as claimed in claim 1 wherein said control voltages are respectively applied to the grids of two valves the current through which varies according to said voltage, and the anodes of the valves are connected respectively to the condensers which are periodically discharged by means of gas-discharge tubes which complete relay circuits.
